UNITED STATES PATENT OFFICE.

EMIL KREBS, OF ELWOOD, INDIANA, ASSIGNOR, BY DIRECT AND MESNE ASSIGNMENTS, TO WILLIAM T. OWEN, OF WASHINGTON, DISTRICT OF COLUMBIA.

FINISHING-TOOL.

SPECIFICATION forming part of Letters Patent No. 792,780, dated June 20, 1905.

Application filed September 17, 1904. Serial No. 224,904.

To all whom it may concern:

Be it known that I, EMIL KREBS, a citizen of the United States, and a resident of Elwood, Indiana, have invented certain new and useful Improvements in Finishing-Tools, of which the following is a specification.

My invention relates to a finishing - tool adapted for use on lamp-chimneys, bottles, or other hollow articles of glassware. It is adapted to open out the ends of such articles, to crimp their lower edges, and to produce a shoulder thereon. I have illustrated my invention in combination with a lamp-chimney, although, as before stated, it is applicable to bottles or other articles of glassware.

Figure 1 of the drawings represents in longitudinal section a tool embodying my invention and a chimney in connection therewith. Fig. 2 is a plan view of a portion of the device detached from the rest.

It is understood that my finishing tool or device is to be used in connection with the ordinary horse or lathe on which the open ends of lamp-chimneys and the like are finished.

As shown it consists of two parts—a socket 1, which is stationary in the lathe, and an opening or shaping portion 2, which is revolved thereby. The socket 1 is provided with a shank 11, in which the shank 21 of the finishing portion 2 rotates. The socket 1 is also provided with a smooth cylindric flange 12, adapted to limit the outer periphery of the bottom of the chimney 3, formed therein, and with an inner transverse flange provided with longitudinally-projecting radially-disposed teeth 13, adapted to form a crimp or a series of radial dentations 31 in the bottom of the chimney 3, similar to those shown at its upper end. The rotating portion 2 of the device is formed with a series of blades 22, (shown as four in number,) adapted to form the neck or lower portion 32 of the chimney. As shown, the blades 22 have a slight abrupt shoulder 23 at their lower ends, by which the lower edge of the portion 32 of the chimney is forced outward to form a bead 33.

The operation of the device will be readily

understood from an inspection of the drawings. It is found desirable in practice to produce a lamp - chimney of the usual "sun" form, the lower edge of which is crimped or dentated, as shown, to permit air to pass thereunder to produce better combustion in the flame of the lamp. It is also advantageous to produce on the outer side of the neck of the chimney a bead, over which the springs of the lamp-burner may engage to prevent the disengagement of the chimney therefrom. When my device is placed within the horse or lathe and the hot chimney, previously blown by hand or machine, applied thereto, it is evident that the teeth 13 in the socket 1 will act to produce the desired indented or crimped effect at the lower edge of the chimney, while the flange 12 will determine the exact outer size of the chimney at its lower end. The rotating blades 21 will act to shape the chimney to the exact size required and by reason of the shoulders 23 at their lower ends will force outward a portion of the glass to form the bead 33 at the foot of the chimney.

It will be seen that a single and rapid operation is all that is necessary to size the chimney, to form the bead on its outer edge, and to crimp its lower end. The finished chimney is then taken by the gatherer to the leer and annealed in the usual manner. It is evident that in some cases it might be desirable to form either the shoulder 33 or the dentations 31 without the other and that for this purpose either the shoulder 23 on the blades 22 or the teeth 13 in the socket 1 might be omitted. It is also evident that other changes may be made in my device without departing from the spirit of the invention.

It will be noted that the abrupt bead at the extreme lower end of the chimney is formed by the action of the shoulders 23 in the blades 22 without any positive forcing inward of the metal above the bead by any inwardly-projecting flange or the like. It will also be noted that the cylindric flange 12 on the socket 1 is of substantially equal diameter its entire

length and freely admits the lower end of the chimney and permits it to be withdrawn therefrom.

What I claim is—

- 5 1. A finishing-tool comprising a stationary socket and a rotatable opening portion, the socket having a transverse flange provided with teeth adapted to produce indentations in the lower edge of the chimney or other article applied thereto, and with a smooth cylindric flange exterior of said teeth for determining the outer diameter of the lower end of such chimney or other article.
- 10 2. A finishing-tool comprising a stationary socket having a smooth cylindric flange, and a rotatable opening portion provided with radial blades having abrupt shoulder portions at their lower ends within said flange, where-

by an outturned bead is formed at the lower end of a chimney or other article applied thereto.

3. A finishing-tool comprising a stationary socket and a rotatable opening portion, the socket having a transverse flange provided with a series of radially-disposed teeth and a smooth cylindric flange surrounding and extending above said teeth, and the opening portion provided with radial blades having abrupt shoulders at their lower end within said flange.

In testimony whereof I have signed this specification in the presence of two subscribing witnesses.

EMIL KREBS.
